Franklin Industries Studded T-Post, 8 ft. 1.25 lb. per foot at Tractor Supply Co. <https://www.tractorsupply.com/tsc/product/franklin-industries-studded-t-post-8-ft125-lb-per-foot> Dec. 27, 2020 (Year: 2020).*Primary Examiner — Leanne Was-Englehart(74) *Attorney, Agent, or Firm* — Zarley Law Firm P.L.C.(57) **CLAIM**

The ornamental design for a fence post, as shown and described.

DESCRIPTION

FIG. 1 is a front perspective view of a fence post;

FIG. 2 is a rear perspective view of a fence post;

FIG. 3 is a front view of a fence post;

FIG. 4 is a rear view of a fence post;

FIG. 5 is a left view of a fence post;

FIG. 6 is a right view of a fence post;

FIG. 7 is a top view of a fence post; and,

FIG. 8 is a bottom view of a fence post.

The dash-dash broken lines depict portions of the fence post that form no part of the claimed design. The dot-dash broken lines depict the bounds of the claim and form no part of the claimed design.
